FLOAT OPERATED SWITCH

James B. Fryar, Dayton, Ohio

Application March 9, 1933. Serial No. 660,183

7 Claims. (Cl. 200—84)

My invention relates to indicators and has particular reference to fluid level indicators; altho, of course, the invention is not to be understood as limited to such use.

5 Briefly stated, the invention has for one of its important objects to provide an indicator which will be especially useful for indicating to the operator of an automobile or other motor vehicle when the level of fluid in the fuel tank has 10 dropped to a predetermined point, the nature of the construction being such that the indicator may include an electrical circuit and switching means without any likelihood of igniting the fuel; the nature of the device being such that it 15 will be positive in operation and will be unaffected by the surging of the fluid as the car or vehicle rocks in transit.

Another object is to provide in an indicator of the kind referred to a novel float-operated switching mechanism, the elements of which are so arranged as to permit free operation of the float to close or open the circuit of the signal when a predetermined level of the fuel in the tank has been reached, the arrangement being 25 such as to prevent the possibility of the float's lagging owing to frictional binding with a wall or guide element.

Still another object of the invention is to provide an electrically operated signal for apprising 30 the driver of the fact when the fuel supply drops to a predetermined point, and which signal includes a circuit having a switch element which will be opened to break the circuit when the ignition switch of the vehicle is opened, and which 35 will assume a closed position when the ignition switch of the vehicle is closed.

The invention further contemplates a novel guide for the float and supporting means for such guide.

40 Other objects are to provide a novel switch element having contacts hermetically sealed so as to prevent gasoline vapor from reaching same; to provide a device including a minimum number of simple parts which may be easily assembled 45 and which will operate positively and reliably for an indefinitely long period of time without the necessity of inspection, adjustment or repair; and further, to provide a device which can be readily installed without the exercise of unusual skill, 50 and which will not in any way detract from the appearance of the vehicle, nor interfere with the operation of it or with the functioning of other apparatus that may be carried by the vehicle.

55 The foregoing and other objects are attained by a novel combination and arrangement of parts

to be hereinafter described and claimed, reference being had to the accompanying drawings illustrating what now appears to be a preferred example of the invention altho it will be apparent that details can be varied considerably within the spirit and scope of the subject matter claimed hereinafter.

In the drawings, wherein the same reference characters have been used to designate the same parts in all views,

60 Figure 1 is a sectional view taken through a portion of an automobile gasoline tank, and illustrating the novel float-operated switching mechanism, the casing and portions of which are shown in vertical section, and the view also illustrating 70 diagrammatically the circuit and the instrument board of the car;

65 Figure 2 is a top plan view of the switching mechanism, with the dome-like cover removed;

75 Figure 3 is a sectional view through the switching mechanism, but illustrating the position same assumes when the level of fuel in the tank is above the predetermined point at which the signal will be actuated, the contacts of the switch being 80 shown separated;

85 Figure 4 is an enlarged rear elevational view of the mounting post carrying certain levers employed in the control of the switch, there also being illustrated a portion of the float rod;

90 Figure 5 is a detail sectional view through a portion of the diaphragm and the cup member to illustrate the securing and sealing means for the joint between the two;

95 Figure 6 is a detail view partly in section illustrating the float rod and stop thereon in association with the base or support of the switch;

100 Figure 7 is an end elevational view of the float-containing casing.

Referring to the drawings by reference characters, and turning to Figure 1, numeral 8 denotes 95 the gasoline tank of a motor vehicle or device, there being the supply line 9 leading from the tank to the carburetor (not shown).

105 In carrying out the invention, the tank 8 is provided with a hole in the top, the margin of 100 which is surmounted by the annulus 10 which may be secured in place in any preferred fashion. Seated upon the annulus 10 is the disk-like closure plate 11 having the circumferential flange 11b seating against the inner wall of annulus 10 so as to make a tight seal, it being observed 105 that there is a packing ring 12 interposed between the members 10, 11 so as to assure of a tight seal. Screws or the like 13 may be used for 110 clamping the members 10, 11 together, and these

screws 13 may be used also for clamping the annulus 10 against the top of the tank 8 about the aforementioned hole.

Figure 1 also clearly illustrates that the under portion of the closure plate 11 has the downwardly projecting ears 11a of which there may be any suitable number, and to which ears is secured the barrel or casing 14. Screws or the like, 14a, may be used for securing the barrel 10 or casing 14 to the ears 11a.

The barrel or casing 14 is provided with one or a number of comparatively large holes adjacent the top of the tank 8 so as to permit the fuel of the tank to flow into the casing 14, it being further observed that there is a hole 14c in the side wall of the barrel or casing 14 adjacent the bottom thereof so as to assure of maintaining the level of the fuel in the barrel or casing 14, equal to the level of fuel in the tank 8. 20 Within the casing 14 is a float 15 having secured to its top the float rod 16 which extends upwardly through the guide-bearing 17c which is provided in the web member 17 carried by the walls of the casing 14. With reference to 25 the web member 17 providing the guide-bearing, as aforesaid, particular attention is directed to the manner of mounting this web member, and assembling it with the casing 14. The web member comprehends a number of preferably radial 30 arms as shown in Figure 7. The ends of the arms of the web member 17 are turned downwardly as illustrated in Figure 1 so as to be received in pockets 18 formed by making a short, horizontal slit in the wall of casing 14 and then 35 bulging the subjacent portion of such wall inwardly as indicated at 18c. When the down-turned ends 17 of the arms of the web member have been seated in the pockets 18, then the 40 stock of the casing wall above the web arms will be pushed inwardly slightly as indicated at 18c, so as to overlie a portion of the arms 17b to hold the web member seated, as will be clearly apparent from an inspection of Figures 1 and 7.

Thus the guide-providing web member 17 can 45 be readily and rigidly assembled in the casing 14 without resorting to the use of solder, welding, or fastening elements such as screws, rivets, or the like.

Still referring to Figure 1, but also having reference to Figure 3, it will be seen that the float-operated rod 16 is provided above the web member 17 with an enlargement providing a stop 19 adapted to engage the bottom surface of the closure plate or disk 11 about the bearing 20 50 when the level of fuel in the tank 8 is at a point substantially above the minimum or "signal-indicated" level, which is denoted by the dotted line α in Figure 1. In other words, the movement of the float vertically in the casing 14 is 55 but a short distance, and one reason, among others, for this is to prevent undesired operation of the low level indicator by surging of the fluid in the tank when the vehicle is in transit.

The float rod 16, as intimated, extends through 60 the central bearing 20 in the closure plate 11, and such rod has a second shoulder 21 adjacent its upper end. The float rod extends with a loose fit through a flange portion of a lever 38 to which reference will be made later on, it being 65 observed that such lever is below the second shoulder or abutment 21 on the rod 16. The engagement of shoulder 21 with the lever 38, as in Figure 1, brings about closing of the circuit to the signal. All this will be referred to in detail later on.

In carrying out the invention, I preferably provide the disk-like closure plate 11 with an upstanding boss 23 providing a support for an angle bracket 22 which is secured to the top of the boss 23 by means of the screw or bolt 24. Obviously, however, other securing means might be used, and the bracket might be secured to the top of the closure plate 11 instead of to a boss such as 23.

Welded or otherwise secured to the upstanding arm of the bracket 22 is a cup member 25, there being a central hole through the upstanding bracket arm and cup member, through which hole passes the binding post 26. The head portion of the binding post within the cup member is provided with the contact 27 which is adapted to engage a companion contact 28 which is carried by a diaphragm 32 secured against the marginal flange 25b of the cup member by the clamp ring 25c and the packing or washer 32b (see Fig- 95 ure 5).

The diaphragm-carried contact 28 may be secured to the diaphragm in any preferred manner, such as by the washers 32c which are secured to opposite sides of the diaphragm at a central point 100 thereon; or the contact 28 may be secured to, or be an integral part of, the adjacent end of a lever member 34 which is secured to the diaphragm, preferably at or about the site of the washers 32c.

Adverting to the binding post 26, it will be observed that the hole through the cup member 25 and upstanding arm of the bracket 22 is considerably larger than the diameter of the binding post, and that a bushing and associated 110 insulation material washer structure serves to insulate the binding post 26 from the cup member 25 and the bracket 22.

Nuts 30 may be used, as usual, for drawing the head of the binding post 26 against the adjacent insulation washer and also for securing the terminal element 31 of the circuit line 31a.

Figure 1 also illustrates that there is a crimped metal strip 33 which connects the contact 28 with the rim 25a of the cup member 25 so as to provide a ground, it being understood, of course, that the cup member 25 is of metal, and it being apparent at a glance that such strip 33 will permit flexing of the diaphragm 32, while at the same time providing a ground for one side of the 125 signal circuit. Strip 33 is held in place by metal ring 25a (Figure 5).

The signal itself that is employed may be of any desired form, but preferably it will be a light S secured to the dashboard of the car or at some 130 other convenient point so as to be readily seen.

The circuit wire 31a leads to the light S, while the circuit wire 31b leads from the light to the battery B which has the ground connection 31c grounded as at G.

Particular importance is attached to the fact that the ignition lock L controls a switch which will be open when the ignition switch is open, and closed when the ignition switch is closed. This is of considerable advantage, as the driver 140 may be apprised that his gasoline is running low at a time when he is almost home and does not want to bother about getting gasoline. When he cuts out the ignition switch L of his car, the signal light S will go off. When he again turns 145 on the ignition switch, the signal will tell him that he needs gasoline.

Reference has heretofore been made to the diaphragm-actuating lever 34 which may carry the contact 28, but which, in any event, controls the 150

movement of the diaphragm 32 and the consequent making and breaking of the signal circuit at the site of the contact 27, 28. The rear end of this lever 34 is pivoted as at 35 to the U-shaped upper end 36, 36' by means of the pin 35. This pin 35 may take the form of a cotter pin as illustrated in Figure 4, and there will preferably be used a sleeve 41 on the pin 35 so as to maintain the rear end of the arm 34 at a point adjacent the upstanding portion 36' of the lever 36, 36'.

10 The control lever 36 is pivoted as at 36a (see Figs. 1 and 4) to the spaced side portions of an upstanding post 37 whose feet are secured to the closure disk or plate member 11 by screws or other desired means as indicated at 37'.

15 Figures 1 and 3 illustrate the control lever 36 as being angular in side elevation and having a depending forwardly extending notched portion 36b providing a catch which is adapted to engage the angular latch portion 38a of a latch lever 38 which is pivoted as at 39 to the lower portion of the post member 37 between the sides thereof as illustrated in Figures 1, 3, and 4.

20 Figures 1, 2 and 3, illustrate the control lever 36 and the latch lever 38 as provided with lateral ears 36c, 38c respectively. The ear 38c of the lever 38 is located much closer to the pivot 39 than to the end 38b providing the bearing through which the upper end of the float rod 16 extends. On the other hand, the ear 36c of the control lever 36 is located adjacent the outer end of such lever and preferably immediately adjacent the laterally turned plate portion x which is adapted to intercept the upper end of the float rod 16 when the float rises above the low level a shown in Figure 1.

25 Inasmuch as the ear 38c is close to the pivot 39, the latch lever 38 will be easily tripped by the shoulder 21 on the float rod when the float 15 drops to a point below the low level a. It is important that the latch lever 38 be easily tripped so as to avoid possibility of the float lagging and failing to drop with the level of the fluid in the tank. On the other hand, the location of the 30 ear 36c of the control lever 36 at a point adjacent the outer end thereof enables the coil spring 40 which connects the ears 36c, 38c to effect positive operation of such lever, and the diaphragm-actuating lever 34 immediately the latch portion 38a of lever 38 disengages from the notch or catch portion 36b of lever 36.

35 It is believed to be apparent that the vertical rocking of the lever 36 will produce a lineal horizontal movement of the diaphragm-controlling or actuating lever 34, and this, by reason of the fact that the connection 35 of lever 34 with the lever 36 is above the pivot point 36a, about which the lever 36 rocks. This point is referred to briefly for the present. The operation will be described later on.

40 A dome-like cover 42 is provided for enclosing the switching mechanism, and it may be secured in place upon the top surface of the closure plate 11 in any preferred manner.

45 The operation of the device may be summarized as follows:

46 When the tank 8 is replenished with fuel to a point above the low level indicated by dotted line a in Figure 1, the float 15 rises, pushing the float rod 16 upwardly through the bearings 17a, 20. The parts of the device at the commencement of this filling operation would be in the position shown in Figure 1. The upward movement of the float 15 and float rod 16 causes the upper end of the float rod to intercept the lateral

extension x of the control lever 36, causing such lever to rock in a clockwise direction. When this happens, the shoulder 21 will have raised off of the bearing portion 38b of the latch lever 38 so that the spring 40 will swing the latch lever 38 in a clockwise direction also, such relative movement of the levers 36, 38 causing the latch portion 38a to engage the catch portion 36b of lever 36, as shown in Figure 3, so as to hold the levers in the position shown in Figure 3.

80 5 The control lever 36 is being moved in a clockwise direction under the influence of the upper end of the rising float rod 16, the pivot 35 which connects the diaphragm-actuating lever 34 to the lever 36 will be moving in a clockwise direction also, although such movement is very slight, and is substantially lineal. Such rearward movement of the diaphragm-actuating lever 34 causes the contacts to be separated as indicated in Figure 3. Thus the signal circuit is open, and the signal S will not be displayed.

85 10 The location of the enlargement or shoulder 19 on the float rod 16 with reference to the closure member or disk 11 is such that such shoulder 19 will engage such disk or plate 11 an instant after the latch portion 38a of lever 38 has engaged the catch portion 36b of lever 36. Thus upward movement of the float and float rod will be stopped immediately the shoulder 19 engages the bottom of plate 11.

90 15 The tank 8 may be filled with fluid right up to the top wall, but the float remains submerged, as will be evident. This is a distinct advantage, as it prevents the float from being affected by the surging of fluid in the tank while the vehicle is 110 in transit.

95 20 The signal S will not be shown and the parts will remain in the position shown in Figure 3 until such a time as the level of fluid in the tank 8 drops to the dotted line indication of Figure 1. At 11b such time the upper shoulder 21 on the float rod 16 will have engaged the lateral bearing portion of the latch lever 38 so as to pull such lever in a counter-clockwise direction about its pivot 39. This disengages the latch portion 38a of such 120 latch lever 38 from the catch portion 36b of lever 36. The spring 40 which connects the levers 36, 38 now comes into play to pull lever 36 downwardly in a counter-clockwise direction which, as a result of the pivot-connection 35 between 125 levers 36 and 34, moves the lever 34 to the left, as viewed in Figures 1 and 3, so as to bring the contacts 27, 28 into engagement as shown in Figure 1. The circuit of the signal S will now be closed, and the signal will apprise the operator 130 that his fuel is running low.

100 25 Of course, it is desired to have the low level a sufficiently above the bottom of the tank so as to give the operator, say, a gallon or a gallon and a half of gasoline, which will be all-sufficient to 135 enable him to get to the next gas station to replenish his supply.

105 30 It will be evident that I have provided a snap-action switch that will be positive and effective in operation. There are no pivots at the site of the contacts 27, 28 which are hermetically sealed so as to prevent any possibility of gas vapor getting thereto. The contacts are also protected against moisture and dirt and the dome-like closure 42 will protect the working parts of the device from the elements, while at the same time permitting ready inspection of same. The lever-carrying post 37 enclosing the pivot ends of the levers, and the U-shaped formation of the levers 36, 38 at the site of their pivots, provides a very 145 35

strong construction. By including the ignition switch L in the apparatus, as a means for operating a cut-out switch, the driver, when starting out in the morning, will be immediately reminded to get gasoline in the event that he was given the "low" signal on his way home the evening before.

Most drivers are careless in watching their gasoline gauges, and furthermore, most gasoline gauges are unreliable in operation, and give the driver only an approximation of the amount of fuel that he has in his tank at a particular time.

The casing 14 protects the float against surging fluid but the holes 14b adjacent the top of the tank enable the casing 14 to be immediately supplied with fuel to the level to which the tank is filled. The small hole 14c adjacent the bottom of the casing 14 will not expose the float 15 nor the interior of the casing 14 to surging fluid in the tank, but will, of course, assure the maintenance of a level of fuel in the casing 14 equal to the level in the tank outside. It is a simple matter to apply the switch and unit to the tank 8, and it is an equally simple matter to apply the signal S to the dashboard. Any desired form of switch to be operated by the ignition switch L can be used; although, of course, preferably the signal switch will be identical with the ignition switch as a part of the lock.

Having thus described my invention, what I claim is:

1. In a low level indicator or the like for fluid tanks including an electric signal and circuit therefor, a base member, a closed casing carried by said base member and having opposed walls, one of said walls being flexible, cooperating contacts within said casing and carried by said walls, said contacts being in and adapted to make and break said circuit, a lever secured to said flexible wall, a control lever for said aforementioned lever and operatively connected thereto, and having a latch engaging portion, a latch member adapted to engage said latch engaging portion of said second lever, a common support for said second mentioned lever and latch member, yielding means engaging said second mentioned lever and latch and tending to actuate said latch against said lever and to actuate said lever to effect engagement of said contacts, float-operated means operable in one direction to actuate said second mentioned lever to separate said contacts and effect engagement of said latch with said latch-engaging portion of said second mentioned lever, and said float operated means having a latch tripping portion adapted to engage and release said latch when moved in the opposite direction whereby, through said yielding means and levers, to effect engagement of said contacts.
2. In a low level indicator or the like for fluid tanks including an electric signal and circuit therefor, a base member, a closed casing car-

ried by said base member and having opposed walls, one of said walls being flexible, cooperating contacts within said casing and carried by said walls, said contacts being in and adapted to make and break said circuit, a lever secured to said flexible wall, a control lever for said aforementioned lever and operatively connected thereto, and having a latch engaging portion, a latch member adapted to engage said latch engaging portion of said second lever, yielding means engaging said second mentioned lever and latch and tending to actuate said latch against said lever and to actuate said lever to effect engagement of said contacts, float-operated means operable in one direction to actuate said second mentioned lever to separate said contacts and effect engagement of said latch with said latch-engaging portion of said second mentioned lever, and said float operated means having a latch tripping portion adapted to engage and release said latch when moved in the opposite direction whereby, through said yielding means and levers, to effect engagement of said contacts.

3. In a fluid level indicator or the like including an electric signal and circuit therefor, a base member, relatively fixed and movable contacts in said circuit and providing a switch, a carrier arm for said movable contact, an operating lever carried by said base and pivoted to said carrier arm, means tending to hold said contacts together, lever actuating means operable in one direction to disengage said contacts, latch means carried by said base for holding said contacts disengaged, and tripping means for said latch carried by said lever-actuating means and operable upon movement thereof in another direction.

4. In a fluid level indicator or the like having an electric signal and circuit therefor, relatively movable contacts in said circuit providing a switch, means tending to hold the contacts together, a lever, actuating means for said lever operable in one direction to disengage the contacts, latch means arranged to hold the contacts disengaged, tripping means for said latch means carried by the lever actuating means and operable upon movement and the latter in the opposite direction, the movements of the lever actuating means and the tripping means being controlled by the level of the fluid.

5. The structure of claim 4, the means tending to hold the contacts together including a spring actuated carrier arm.

6. The structure of claim 4, the means tending to hold the contacts together comprising a spring actuated carrier arm pivoted to the lever.

7. The structure of claim 4, the means tending to hold the contacts together comprising a carrier arm pivoted to the lever and a spring controlling the lever and latch means.

JAMES B. FRYAR.
